UNITED STATES PATENT OFFICE.

JOHN G. REBER, OF CHICAGO, ILLINOIS, ASSIGNOR TO J. W. SEFTON MANUFACTURING COMPANY, OF ANDERSON, INDIANA, A CORPORATION OF INDIANA.

FOLDING BOX.

No. 900,953.

Specification of Letters Patent.

Patented Oct. 13, 1908.

Application filed August 14, 1906. Serial No. 330,535.

To all whom it may concern:

Be it known that I, JOHN G. REBER, a citizen of the United States, residing at Chicago, in the county of Cook and State of Illinois, have invented certain new and useful Improvements in Folding Boxes, of which the following is a specification.

My invention relates to what are commonly referred to as folding boxes and the object thereof is to provide such box with simple and efficient means whereby the box, after being filled and sealed, can be readily opened either for removing the goods or for the permitting of inspection thereof, such opening of the box being done without any liability of damage to the contents. Moreover, according to my invention, a strip is arranged on the inner sides or surfaces of a plurality of the side walls of the box to cover and conceal a tearing tape or string interposed between it and the side walls and also to form a flange for the end or top of the box which becomes torn or detached from the main body of the box so far as the particular side walls having the tearing tape or string are concerned.

In the drawings, Figure 1 is a perspective of a blank from which the box is formed; Fig. 2 a perspective of the box in folded condition as to its side walls, but in open condition as to the end extensions which, when folded, form the top and bottom covers or closures of the box; Fig. 3 a perspective of the strip which is secured to the side walls—to three of the side walls in the present instance—and also illustrating the tearing tape or string; Fig. 4 a perspective of the box in complete or assembled form and illustrating the method of opening the box by the pulling of one end of the tape which is herein shown as having partially torn one of the side walls; Fig. 5 a cross section of the box illustrated in Fig. 3, but with the lid shown thrown open; and Fig. 6 a section on a somewhat enlarged scale taken on the line 6—6 of Fig. 4.

My invention may be embodied in folding boxes of different character and of different construction, but for the sake of a clear and definite description I have chosen to illustrate the same in connection with a folding box of rectangular form and made from what is known as double-faced corrugated paper board which gives the requisite strength and rigidity for boxes of this char-

acter, to be used more particularly as shipping boxes and the like.

Referring to the embodiment of my invention as illustrated in the drawings the blank from which the box is formed is illustrated in Fig. 1 and comprises four side walls, 1, 2, 3 and 4, which are provided at their opposite ends with extensions 1^a, 2^a, 3^a and 4^a which are hinged thereto. The said side walls may be all hinged together by their own material, but by preference I make the fourth wall 4 separate from the others and hinge the same to the side walls 1 and 3, respectively, by the tapes 5 and 6, which when pasted or otherwise secured to said side walls, serve as hinges. Upon the inner face or surface of a plurality of these side walls, in the present instance the side walls 1, 2 and 3, and at or near one edge, either top or bottom edge, of the side walls, I secure in any suitable manner a strip 7, which, as illustrated in Fig. 3, is composed of three sections hinged together and corresponding in length to the width of said side walls 1, 2 and 3. In the present instance, and by preference, the outermost edge of this strip comes flush with the top edge of the side walls 1, 2 and 3, and in the present instance also and by preference, this strip is pasted to the inner surface of said side walls by gluing at its innermost edge, thereby leaving the upper or remaining portion of the strip unattached to the side walls, but nevertheless in close or intimate contact therewith.

Between the strip 7 and the side walls is laid or interposed what I will term a tearing tape or strip 8, which is slightly longer than the strip 7, so that its free ends may be extended extraneous of the box and may be grasped and pulled upon by the operator in the manner and for the purpose hereinafter described. Although this tearing tape or string may be simply laid between the strip and the side walls, yet it is preferred to position it rather close to the gluing or pasting line so that its innermost edge may be firmly held in such position either by the intimate contact alone of said parts or both by said contact and a small portion of the glue which is expressed between the parts. This strip serves a double function, inasmuch as it not only covers and conceals the tearing tape or strip, but also constitutes a flange projecting from the body of the box after the opening

operation hereinafter described. The tearing strip by preference is not made of corrugated paper board such as the body of the box, but of a rather heavy stock of ordinary paper board, as commonly used in folding boxes, the weight of the stock being dependent upon the size and required strength of the box as a whole.

In practice, the box is first set up to the condition illustrated in Fig. 2, whereupon that end of the box which is to constitute the bottom is closed by folding in the end extensions the extensions from opposite sides being folded inwardly, the narrower sides being preferably folded in first, after which the longer sides are folded and by preference firmly secured to the other pair of extensions in suitable manner, as by pasting or gluing, with the result that the end of the box is closed and concealed. The box is now ready to be filled with the goods and after the same are introduced therein those end extensions which are to form the top of the box are folded inwardly and sealed in the same manner as the bottom extensions, as already described. It will be understood that at this time one or both of the free ends of the tearing tape extend extraneous of the box in position to be grasped and pulled by the operator. In this operation the body of the side walls is torn along the line on which the tearing tape lies, such tearing line being in a horizontal plane when the box is positioned, as illustrated in Fig. 4, wherein the box is shown as partially torn. A continuance of this tearing operation across all three of the side walls 1, 2 and 3 will cause a severance or separation between the top end of the box and a small portion of the side walls which remain fastened to the end extensions, the top remaining attached or hinged to the fourth side wall 4 and thereby constituting a lid, as illustrated in Fig. 5. According to this construction, the detached portions of the side walls now constitute flanges for the lid, while that portion of the strip 7 projecting above the line of severance of the side walls constitutes a meeting co-operating flange for the flanges of the lid. In this manner and by these means, a folding or shipping box of the character described, may be quickly and conveniently opened, notwithstanding the fact that the same has been securely closed and sealed and this without any damage or possibility of injury to the contents of the box. Moreover, the box is not destroyed as the result of the opening thereof, but on the contrary the top which is partially separated or detached from the body of the box remains as a lid, with the result that the box may be sealed up again in case it had been opened for inspection, or may be continued in use as a container for the goods after being opened by the consumer or jobber.

As hereinbefore stated, the construction illustrated is the preferable one, although, as will be understood, changes or modifications may be adopted without departing from the spirit of my invention. For instance, the strip 7 and the tearing tape 8 may be extended so as to cover and co-operate with all four sides of the box, in which event the tapes 6 and 7 could be transversely slotted at the tearing line of the tape. 75

In practice and as herein shown, where the double-faced corrugated paper board is employed as the material for the box, the corrugations run transversely of the body of the box and the tape or string runs parallel with said corrugations, with the result that when such tape or string is pulled, the side walls forming the body of the box are severed along a line of the corrugations, such severing action being more easily and readily done with this relative arrangement of the corrugations and tape or string. 80 85

I claim:

1. In a folding box, the combination, with the side walls thereof and with end extensions hinged thereto and secured together to form top and bottom covers, of a strip secured to the inner face of the side walls near one end thereof, and a tape or string interposed between the strip and the side walls 90 and adapted, when pulled, to tear through the body of the side walls and open the box. 95

2. In a folding box, the combination, with the side walls thereof and with end extensions hinged thereto and secured together to form top and bottom covers, of a strip secured to the inner face of the side walls with its outermost edge substantially flush with the top edge of the side walls, and a tape or string interposed between the strip and the 100 side walls and adapted, when pulled, to tear through the body of the side walls and open the box. 105

3. In a folding box, the combination, with the side walls thereof and with end extensions hinged thereto and secured together to form top and bottom covers, of a strip secured at its innermost edge to the inner face of the side walls, and a tape or string interposed between the strip and the side walls 110 115 and adapted, when pulled, to tear through the body of the side walls and open the box.

4. In a folding box, the combination, with the side walls thereof and with end extensions hinged thereto and secured together to 120 form top and bottom covers, of a strip glued at its innermost edge to the inner face of the side walls, and a tape or string interposed between the strip and the side walls and adjacent the pasting line and adapted, when 125 pulled, to tear through the body of the side walls and open the box.

5. In a folding box, the combination, with the four side walls thereof and with end extensions hinged thereto and foldable and se- 130

cured together to form top and bottom covers, of a strip secured to three of the side walls at one end thereof and to the inner face of the same, and a tape or string interposed between the strip and the said three side walls and adapted, when pulled, to tear through the body of the side walls and open the box.

6. In a folding box, the combination, with the four side walls thereof and with end extensions hinged thereto and foldable and secured together to form top and bottom covers, said walls and extensions being formed of double-faced corrugated paper board, of a strip formed of ordinary paper board and thinner than said corrugated board and secured to three of the side walls at one end thereof, and a tape or string interposed between the strip and said three side walls.

7. In a folding box, the combination, with the side walls thereof and with end extensions hinged thereto and foldable upon and secured to each other to form top and bottom covers, of a strip glued at its innermost edge to the inner face of the side walls, and a tape or string interposed between said strip and side walls and adjacent the glue line in position to be slightly retained by the glue.

8. In a folding box, the combination, with the side walls thereof and with end extensions hinged thereto to form top and bottom covers, a tape or string positioned at the inner face of the side walls, and a strip secured to three of the side walls transversely thereof and on the inner face thereof, said strip being arranged to serve as a cover for the tape and as a flange for one end of the box when separated from the body thereof by the act of pulling the tape and thereby cutting through said three side walls.

9. In a folding box, the combination of the four side walls hinged together to form the body of the box, extensions hinged to the opposite ends of said walls and adapted to be secured together to form the ends of the box, a strip secured to the inner face of three of the side walls near one end thereof, and a tape or string adapted, when pulled, to tear through the body of said side walls and thereby open the box.

10. In a folding box, the combination of the four side walls hinged together to form the body of the box, extensions hinged to the opposite ends of said walls and adapted to be folded over in pairs from opposite sides of the box and to be secured together to form the ends of the box, a strip secured to the inner face of three of the side walls near one end thereof, and a tape or string adapted, when pulled, to tear through the body of said side walls and thereby open the box.

11. In a folding box, the combination of a box proper formed of double-faced corrugated paper board and consisting of side walls hinged together and end extensions adapted to be secured together to form the ends of the box, the corrugations of the board running transversely of the body of the box, a thin paper strip secured to the inner face of three of the side walls of the box, and a tape or string interposed between the strip and said side walls and extending parallel with said corrugations, whereby when the tape is pulled the three side walls are severed along the line of the corrugations.
